BENJAMIN W. MEISEL, OF CRESTWOOD, NEW YORK, ASSIGNOR TO THE REGAN SAFETY DEVICES COMPANY, INC., OF NEW YORK, N. Y., A CORPORATION OF NEW YORK

TRAIN CONTROL SYSTEM

Application filed October 1, 1926, Serial No. 138,873. Renewed July 18, 1932.

This invention relates to a train control system and more particularly to a system for controlling the movement of trains automatically by roadside mechanism and manually by the engineman on the train and has special reference to the provision of a system which in combination with the automatic features includes cab signals so arranged that, as the train enters each block a cab signal indication is received, and retained throughout the block, for the block entered and in addition, and at the same time, a second cab signal indication is received and retained throughout the block, for the block next ahead.

15 This combination of a duplex cab signal with its control equipment embodies one of the principal objects of my present invention, which comprehends the provision of a train control system of the intermittent type in which the train carried mechanism for governing the operation of the train is automatically controlled by roadside mechanism operable in accordance with roadside conditions, without the necessity of having, in combination therewith, operating roadside signals. There is nothing in my present invention, however, which will prevent its proper operation in combination with roadside operating signals.

20 In the production of an effective train control system, that may be used without operating roadside signals, one of the factors of paramount importance is that of providing advance information, preferably in the form of a cab signal, of the condition of the block which the train is approaching so as to enable the engineman, if necessary, to apply the brakes in the usual manner, thus preventing an automatic application of the brakes at the 25 next roadside control point providing the train is then running at a safe speed and also, providing the engineman acknowledges his alertness as to the conditions on the track and as reflected in the cab signal by manually operating an acknowledging device which is part of the train control system.

25 This combination of automatic train control with duplex cab signals, permits the safe movement of trains in foggy and stormy 30 weather, since the engineman is fully advised

at the entrance of each block not only of the conditions of the block being entered but also as to the condition of the block next ahead. To operate trains under foggy and stormy weather conditions, where roadside operating signals only are used, is a hazard because the engineman cannot see the indications of the roadside signals and in order to come within the realm of safety, all trains must move at a much lower rate of speed than normal. Without advance information as to the condition of the blocks the engineman cannot safely increase the speed of his train. Under foggy and stormy weather conditions, with automatic train control and roadside operating signals, but without duplex cab signals, as well as with automatic train control without roadside operating signals or duplex cab signals exhibited under all weather conditions, the engineman would practically be forced to operate his train at reduced speed. Without advance information by means of signal indications, the engineman is not prepared to handle his train to the best advantage, because of the possibility of receiving an unexpected automatic application of the brakes. To receive an unexpected application of the brakes is sometimes a hazard and usually a handicap to the engineman in obtaining the best results for efficient and safe 35 train operation. It is therefore, the principal object of my present invention to provide a system of automatic train and cab signal control which will be a help rather than a handicap to the engineman in handling properly the movement of his train, but will restrain him from shifting or casting the full burden of control upon the automatic train control mechanism; substitution of automatic mechanism alone for the engineman being 40 highly undesirable in practice.

45 The ideal method of controlling the movement of trains by automatic train control is that in which the engineman is compelled to be alert, or is deterred or restrained from being remiss in his duties associated with the signals and train control, so that proper handling of the train is enforced and in which the engineman is supplanted by the automatic control mechanism only upon his failure prop- 50 55 60 65 70 75 80 85 90 95 100

erly to discharge his duties. When so sup-
planted, the automatic control is the domi-
nant factor until safe running conditions of
the train are restored and the engineman
again assumes control. When the engine-
man and the automatic train control mecha-
nism are made to cooperate in this manner,
the one acting as a check upon the other, ab-
solute safety and proper dispatch in the run-
ning of trains is assured.

By my present invention, to accomplish
this object, I provide a train control system
in which full control of the train is left in
the hands of the engineman so long as he
properly performs his duties in conformity
with the indications received from the road-
side signalling apparatus and which indica-
tions are reflected in the duplex cab signal
combination. On the other hand if the en-
gineman is incapacitated or remiss in the per-
formance of his duties in accordance with
roadside conditions then the control of the
train is automatically taken from the engine-
man. The engineman is thus compelled to be
alert and operate his train in accordance with
an "unsafe" roadside condition and compelled
to acknowledge such "unsafe" condition in
order to prevent an automatic application of
the brakes. If the engineman is remiss in
preventing this automatic operation, he is
thereafter compelled to be alert and again to
take charge of the movement of the train in
order to avoid an automatic stopping of the
train. Thus this system combines the factor
of absolute safety by making train operation
dependent upon the automatic dictation of
the roadside mechanism under unsafe condi-
tions with the factor of proper train dispatch-
ing by making the efficient movement of the
train dependent upon the activity and alert-
ness of the engineman.

Another principal object of my invention
is to embody the speed control features and
cooperative parts of the train control sys-
tem as disclosed in the Shaver-Meisel Pat-
ent No. 1,513,562, in which the vehicle is con-
trolled and forced to operate within permis-
sive speed limits. The roadside mechanism
imposes automatically such restrictions as a
medium speed at or below which the vehicle
must approach points of danger in localities
where a greater speed would be unsafe, and
a low speed above which the vehicle cannot
run in "danger" localities, as in blocks occu-
pied by other trains. In accomplishing this
object of the invention, the design and con-
struction of the system is such, that if a
speed greater than the permissive medium
speed is attempted when roadside conditions
require the movement of the vehicle at or
below the medium speed, the train is auto-
matically controlled to bring the same to a
halt, the alertness of the engineman permit-
ting, however, the placing of trains under
the control of the medium permissive speed.

If a speed greater than the low permissive
speed is attempted when the roadside con-
ditions require a low speed restriction on the
train, the train is automatically controlled
to bring the same to a halt unless the engine-
man again modifies the automatic operation
to place the train under the control of the
low permissive speed.

To the accomplishment of the foregoing
and such other objects as may hereinafter
appear, my invention consists in the elements
and their relation one to the other as here-
inafter particularly described and sought to
be defined in the claims; reference being
had to the accompanying drawings showing
the preferred embodiment of my invention
and in which:—

Fig. 1 is a diagrammatic view showing the
vehicle carried apparatus and circuits;

Fig. 2 is a diagrammatic view showing the
roadside apparatus and circuits;

Fig. 3 is a detail showing of the ramp con-
struction;

Fig. 4 is a diagrammatic illustration of
the track and the blocks shown in Fig. 2; and

Figs. 5, 6, 7 and 8 show the signals re-
ceived by the vehicle.

Referring now more in detail to the draw-
ings I will first explain in a general way
how the circuits of Figs. 1 and 2 may be
combined so as to give a composite concep-
tion of what my present invention intends
to accomplish, following which I will de-
scribe in detail, the circuits involved and the
functions of the apparatus connected thereto.

In Fig. 2, the circuits shown are for four
signal blocks designated as C, D, E and F.
Block F is occupied by train a. Train b,
at the left of the drawings, is approaching
block C. These blocks and positions of trains
are identical with the arrangement of blocks
and trains shown in Fig. 4. The four sym-
bolic diagrams of the vehicle carried signals,
as shown in Figs. 5, 6, 7 and 8 illustrate the
indications displayed by the signal unit of
train b as it progresses and passes into and
through each of the blocks C, D, E and F,
providing train a still occupies block F.
The symbol X in the squares of the cab sig-
nal diagrams indicates the signals displayed.
The signals in the column B indicate the con-
dition of the block in which the train is run-
ning after passing over indicating ramps
c-d-e and f respectively. The signals in col-
umn A indicate the condition of the advance
block or the block next ahead after passing
over the indicating ramps just mentioned.
G, Y and R indicate green for "clear", yel-
low for "caution" and red for "occupied
block" which are, to a large extent, the uni-
versal indications used for railroad signal-
ing.

These indications may be displayed in the
cab or any other part of the vehicle con-
venient for the observation of the engineman

or operator of the vehicle. Any type or kind of signal may be used so long as it is distinctive and capable of being controlled primarily by means of electrical circuits.

- 5 Fig. 2 as explained heretofore, shows the roadside block circuits for the number of blocks mentioned. The symbols for signals along the track are shown dotted and are included in Fig. 2, as well as in Fig. 4, merely to show the indication of the various blocks due to the presence of train *a* in block F. The circuits as well as the apparatus associated with each block in Fig. 2, as to electrical condition and position of relay contacts correspond to the indications shown for the respective blocks. In other words the circuits and apparatus are shown in their actuated position or electrical condition with respect to train *a*; and the function of these circuits and controlling relays is to energize each of the ramps *c*, *d* and *e* in such a way that six indications are possible on each ramp due to the presence of electrical energy; said indications always occurring in pairs, as for example "green, green", "green, yellow", "yellow, red"; and a seventh, single indication of red for a ramp, as for example *f*, adjacent to or at the entrance of occupied blocks. Such ramps are always deenergized.
- 10 To produce these six (but always recurring in pairs) indications, I have employed ramps at the entrance of each block. These are insulated preferably at the middle so as to permit electrifying these ramps—each end separately—either from the same source of energy or from an independent source, as may be required. The roadside wiring system is preferably so designed that the leaving end of the ramp is energized to indicate the condition of the block in which the train is running and the entering end indicates the condition of the advance block or the block next ahead. For example, ramps may be energized positive (+) at both ends to produce an all clear or "green, green" signal; positive (+) at one end and negative (-) at the other to produce the "clear, caution", or "green, yellow" signal; and negative (-) at both ends to produce the "caution, danger" or "yellow, red" signal. As explained before, deenergized ramps, that is without either end being electrified, produce the "occupied block" or "red" signal. It is understood, of course, that when the ramps are energized the adjacent rail, preferably, is also energized. The rail is negative (-) when both ends of the ramp are positive (+), and positive (+) when both ends of the ramp are negative (-); and both positive (+) and negative (-) when the ramp is energized negative (-) at one end and positive (+) at the other.
- 15 Figs. 5, 6, 7 and 8 are so designated with relation to Fig. 4 as to show clearly the signals indicated by each ramp.

Fig. 5 which is disposed adjacent to the ramp C shows that the ramp indicates and the cab will receive two green signals to show that blocks C and D are "clear".

20 Fig. 6, adjacent to ramp *d*, shows that the ramp indicates clear for block D and caution for block E, and that the cab will exhibit the corresponding signals, green and yellow.

25 Fig. 7, adjacent to ramp *e* shows that the ramp indicates caution for block E and danger for block F. The cab will, therefore, receive the signals yellow and red.

30 Fig. 8, adjacent to ramp *f* of Fig. 4, shows that ramp *f*, indicates danger and the cab will, therefore, receive one red signal.

35 In order to prevent a short circuit of the roadside source of energy, with resultant heavy flow of current, as the shoe S, Fig. 1, passes over a ramp at its insulated section, when each end is of a different polarity, I have shown in Fig. 3, the ramp divided into three sections *S'*, *S²* and *S³*. The air gaps *i*—*i* between these sections serve as insulation; although the sections may be insulated in any suitable way. The middle section *S²* is never energized; it simply serves as extended insulation and should be long enough to prevent shoe S from bridging sections *S'* and *S³*. On the other hand the length of *S²* should be the minimum permissible, so as to shorten the dead space over which shoe S must pass. To take care of this momentary opening of the shoe circuit as shoe S passes over energized ramps, the selector I, Fig. 1, is made slow acting in its drop away after its starter ST has been de-energized. It is evident that if the length of the contact on shoe S is diminished so also, may the length of section *S²* of the ramp be diminished. Theoretically at least, this shortening up could be carried to a point where section *S²* would be unnecessary, leaving only sections *S'* and *S³* with insulating material between these two sections, similar to the end posts of insulated rail joints. Under such circumstances, the contact surface of shoe S should be no longer than the thickness of the insulation between the ramp sections.

40 Referring again to the circuit diagram Fig. 2, it will be noted that at the entering end of each block there are, in addition to the track relay, two other control relays; one for the first block and another for the second block. This combination provides the means for energizing the ramp and producing the indications heretofore described and may be applied in substantially the same manner to railroads for single track operation. These circuits combined with the circuits and devices shown in Fig. 1 provide for the cab signals mentioned and also for the train control features. The engine carried contact shoe with its connected apparatus pick up on the approach end of the ramp, the indication

45 50 55 60 65 70 75 80 85 90 95 100 105 110 115 120 125 130

for the cab signal for the second block and on the last half of the ramp the indication for the cab signal for the block being entered and also the train control indication. The operation is such that as the shoe rides over a ramp, the cab signals all become deenergized. This in itself signals the engineman or operator that a ramp is being passed over. As soon as the shoe leaves the ramp the proper signals are displayed; and they remain displayed until they are altered by a subsequent ramp. As will become further clarified hereinafter, in the event the block being entered is clear and the next one "caution" there is no operation of the train control even though the entering end of the ramp is of negative polarity which is the polarity on caution ramps. On caution ramps the train control operation does not take effect until after the shoe leaves the ramp. This arrangement is provided in order to avoid a train control application of the brakes on high speed trains entering a clear block with the next block at caution. Under this circumstance the entering end of the ramp is negative (-) and the leaving end is positive (+); this change of polarity reverses the contacts of the selector I, Fig. 1, first from high speed or clear running to medium speed or caution and then back to high speed. Whenever the train passes over a ramp having its leaving end energized negatively, as in the case of ramp *e* disposed at the entrance to block *E*, the train is put under the control of the speed controller SC. The train carried circuits are put in such a condition that whenever the train exceeds a medium speed an application of the brakes will take place. The system, however, is so arranged that if the engineman is alert and wishes to proceed at or below the medium speed he must perform a manual act by operating the non-sticking switch P'. This act nullifies the automatic brake application, and the train may then proceed again at or below the medium speed, the train nevertheless still remaining under the control of the speed control mechanism SC.

Whenever deenergized ramps are encountered the train control takes effect at once unless the speed is at or below a prescribed low rate and the engineman or operator of the vehicle closes the contact of the switch P. In other words, before a train may enter an occupied block the engineman must acknowledge the fact that he is entering an occupied block even though his speed be below the permissive speed in order to prevent an automatic application of the brakes. Once the train has entered the occupied block the train again is under the control of the speed control mechanism SC and an application of the brakes will automatically take place as soon as the low speed is exceeded. When this happens the engineman may again restore conditions that existed prior to the automatic ap-

plication of the brakes by the manual act of operating the non-sticking switch P'. This act will again permit the train to proceed at or below the low speed, the train again remaining under the low speed control of the speed control mechanism SC.

In describing the operation, it will at times become necessary to refer to certain circuits which had already been traced in an earlier portion of the specification. In order to avoid needless repetition, each of the circuits will be given a designated number and will hereinafter be referred to by that number. In view of the number of circuits involved, a brief statement of the circuits and their functions is given in the following tables. The circuits are divided into three groups. The first group includes the circuits, either complete or partial circuits which exist in the roadside system. The second and third groups relate to circuits which appear in the train carried system. Of these the second group includes the circuits of the selector operating devices and the circuits of the signals and the third group includes the train control circuits.

Roadside circuits

Circuit number	Function performed by the circuit	
One	Energizes rail negatively when immediate block and block next ahead are clear.	95
Two	Energizes leaving end of ramp positively when immediate block is clear.	
Three	Energizes entering end of ramp positively when block next ahead is clear.	
Four	Energizes relay II for clear indication of immediate block.	
Five	Energizes relay CH for clear indication of block next ahead.	
Six	Energizes entering end of ramp negatively when block next ahead is under caution condition.	100
Seven	Energizes relay CH for caution indication of block next ahead.	
Eight	Energizes the leaving end of a ramp negatively when immediate block is under caution condition.	
Nine	Energizes the entering end of ramp negatively when block next ahead is under danger condition.	105
Ten	Energizes relay H for caution indication of immediate block.	

Vehicle carried signals circuits

Circuit number	Function performed by the circuit	
Eleven	Partial circuit for selector starter magnet ST.	
Twelve	Circuit for magnetic clutch of selector I.	
Thirteen	Common return partial circuit for signals RA.	
Fourteen	Green B signal circuit.	
Fifteen	Green A signal circuit.	
Sixteen	Energizing relay I' when RO occupies p ² position.	115
Seventeen	Stick circuit for relay I' when shoe S is on ramp having negatively energized entering end.	
Eighteen	Energizing relay II'.	
Nineteen	Stick circuit for relay I ² .	
Twenty	Yellow A signal circuit.	
Twenty-one	Yellow B signal circuit.	
Twenty-two	Red A signal circuit.	120
Twenty-three	Red B signal circuit.	

Vehicle carried train control circuits

Circuit number	Function performed by circuit	
Twenty-four	Normal circuit for brake valve magnet M.	125
Twenty-five	Normal circuit for reset magnet RS.	
Twenty-six	Medium speed control circuit for the brake valve magnet M and RS.	
Twenty-seven	Auxiliary medium speed control circuit for the brake magnet M and RS when shoe S is on caution ramp.	
Twenty-eight	Low speed control circuit for the brake valve magnet M and RS.	130

Circuit number Function performed by circuit
 Twenty-nine Auxiliary low speed control circuit for
 brake valve magnet M and RS through
 manual switch P.
 Thirty Signal L circuit.

5 I shall now proceed with a detailed description of the roadside circuits and their manner of operation for the purpose of properly energizing the roadside ramps. An inspection of Figure 2 will show that the wiring system of each block and the connections of one block to that of the next succeeding block are identical in each case. I, therefore, utilize the same reference numerals when applied to corresponding parts of the various 10 blocks, and distinguish them by the aid of the characters *c*, *d*, *e*, and *f*.

15 As was pointed out hereinabove each block is provided with a two part ramp at its entrance. The wiring system associated with each of these ramps includes two neutral-polarized relays *H* and *CH*.

20 The relay *H* is responsive to the condition of the immediate block and is energized in one direction by circuit number four when the immediate block is clear, in the opposite direction by circuit number ten when the immediate block is in caution condition, and is deenergized when the immediate block is in danger condition. This relay controls the 25 position of the polarized pole shifting armatures 20, 30 and thereby determines whether the leaving end of the ramp should be energized positively or negatively. The relay *H* also controls the armatures 17 and 33, which 30 are in the circuit between the battery 27 and the leaving end of the ramp and the rail respectively. When the relay *H* is deenergized the armatures 17, 33 break the battery connection to the ramp and track.

35 The relay *CH* in each block is responsive to the condition of the block next ahead of the immediate block. It is energized in one direction, or in the opposite direction, or it is deenergized depending on whether the block next ahead is in clear, caution, or danger condition. The circuits controlled by 40 this relay have a cooperative relationship with the circuit controlled by relay *H* so that when the block next ahead is clear the entering end of the ramp receives a positive energization from the same source as the leaving end of the ramp. When the block next ahead is under caution, the relay *CH* is energized in the opposite direction, and the circuit controlled by it for the negative energization of the entering end of the ramp is independent 45 of the circuit controlled by relay *H*.

50 When relay *CH* is deenergized the entering end of the ramp will be energized negatively provided the immediate block is unoccupied, otherwise the entering end of the ramp will be deenergized. The wiring system of each block is also provided with a battery *B* which serves as a source of energy for the relay *H* of the preceding block and for the relay *CH* 55 of the next preceding block. An unpolar-

ized pole changer 62, 72 is associated with each battery *B*, the pole changer being under the control of the corresponding relay *H*. It will thus be seen that the direction of energization of relay *H* of one block and of the relay *CH* of the preceding block is always the same.

60 It is understood, of course, that in actual operation the wiring system of each block passes through the four stages indicated in Figure 2 as a train passes its ramp and travels on passing through the next four blocks. Considering, for example, the wiring system associated with ramp *f*, it will remain in the condition indicated as long as 65 train *a* is in block *F*. When the train enters the first block beyond *F* the system associated with ramp *f* will assume the condition of the system associated with ramp *e* in Figure 2. When the train passes into the second block 70 beyond *F* the system associated with ramp *f* will assume the condition of the system associated with ramp *d* in Figure 2. When the train *a* passes into the third block beyond *F* the wiring system of the ramp *f* will 75 assume the condition of the system or ramp *c* in Figure 2.

80 The circuits shown in Figure 2 are in their actuated conditions and correspond to the conditions necessary for imparting to the ramps the desired signals. Blocks *C*, *D* and *E* are unoccupied. Both blocks *C* and *D* are therefore, clear. The ramp *c* which is disposed 85 at the entrance to the block *C* and is designed to give an indication of the conditions of the blocks *C* and *D* should, therefore, be so energized as to give clear indications on both its entering and leaving ends. In accordance 90 with the present invention a positive energization corresponds to a clear condition. The roadside circuits are, therefore, so designed that under the conditions indicated 95 both the entering and leaving ends of the ramp *c* will receive a positive energization.

Energization of ramp for two clear indications

100 The battery 27 shown in the wiring system associated with the ramp *c* serves as a source of positive energy for both ends of the ramp *c*, the negative side of the battery 27 being connected to the rail adjacent to the ramp *c* by means of the following circuit:

Circuit number one

105 Negative terminal of battery 27, conductor 28, contact 29 and polarized armature 30 of the relay *H*, conductor 31, contact 32 and armature 33 of the relay *H*, conductors 34 and 35 to the rail adjacent to the ramp *c*.

110 As stated above, the positive side of the battery 27 is connected to both ends of the ramp *c*. The circuit which connects the pos-

itive end of the battery 27 to the leaving end of the ramp *c* is as follows:

Circuit number two

- 5 Positive side of battery 27, conductors 26 and 25, contact 24 and armature 23 of the relay CH, conductor 22, contact 21 and polarized armature 20 of the relay H, conductor 19, contact 18 and armature 17 of relay H, conductor 16 and conductor 15 to the leaving end of ramp *c*.
- 10 The entering end of the ramp *c* is energized positively by the following circuit:

15 *Circuit number three*

- This circuit begins at the positive terminal of battery 27 and follows circuit number two through conductor 16 and then proceeds along conductors 43 and 42, contact 41 and polarized armature 40 of relay CH, conductor 39, contact 38 and armature 37 of relay CH, and conductor 36 to the entering end of the ramp *c*.

It will be seen from the above that the application of positive energization to both ends of the ramp *c* depends upon the directions in which the line relay H and the line relay CH are energized. In the condition of the circuits shown in Figure 2 the line relay H is energized in such a way as to hold its armatures 17 and 33 in contact with their cooperating contacts and to hold the polarized armatures 20, 30 in the position shown. The line relay H is energized by the following circuit:

Circuit number four

- The positive side of the battery Bd, conductor 60d, contact 61d and armature 62d, of line relay Hd, contact 63d and armature 64d of track relay TD1, conductor 65d, contact 66 and armature 67 of track relay TC2, contact 68 and armature 69 of track relay TC1, line relay H, conductors 70, 6, 7, 6d, 71d, armature 72d and contact 73d of line relay Hd and back to the negative side of battery Bd. In view of the fact that the block C which may be subdivided into the sections shown (each section controlling a different track relay—TC1 and TC2) is clear, the corresponding track relays TC1 and TC2 are energized and the circuit traced above is completed through the armatures controlled by these track relays. The direction of energization of the relay H, however, is controlled by the pole changer which comprises the armatures 62d and 72d of the line relay Hd of the block D. In the present instance Hd is energized so that battery Bd is imposed upon the line relay H in such a manner that the pole changer 20, 30 associated with the ramp *c* is in the position indicated and positive energy is applied to both ends of the ramp *c*.
- 65 The connection between the positive side of

the battery 27 and the ramp *c* is further controlled by the condition of the relay CH. The relay CH receives its energization current from battery Be by the following circuit:

Circuit number five

The positive side of battery Be, contact 61e and armature 62e of the line relay He, contact 63e and armature 64e of the track relay TE1, conductor 65e, contact 66d and armature 67d of track relay TD2, contact 68d and armature 69d of the track relay TD1, conductor 74d, armature 2 and contact 3 of line relay H, conductor 4, relay CH, conductors 5, 6, 7, 7d, 6e, 10e, 11e, armature 72e and 73e of line relay He, and back to the negative side of battery Be.

The circuit just traced energizes the relay CH in such a manner that the armatures controlled thereby occupy the positions indicated in Figure 2. From the above, it will be seen that the two relays H and CH co-operate with each other in such a manner as to impose the proper signals on the two ends of the ramp *c*. The directional energization of the relay H in every block is controlled by the line relay H immediately ahead, whereas the relay CH is controlled by the line relay of the block next ahead. It is in this respect that I have departed from standard practice by introducing at a given point two distinct indications: one for the immediate block and one for the block next ahead. The indication for the block next ahead is obtained primarily through the CH relays, controlling energy for which is obtained through the circuit of the H relay next ahead.

Another way of facilitating the understanding of the relationship between the different parts of the circuits shown in Figure 2 is to bear in mind the fact that each of the batteries such as for example battery Be serves as a source of energy for the immediately preceding neutral polar relay Hd, and also for relay CH at the ramp *c* behind line relay Hd.

Energization of ramp for clear caution indication

Ramp *d*, which precedes block D should under the traffic conditions illustrated in Figure 2 indicate clear for the block D and caution for block E. The leaving end of the ramp must, therefore, be energized positively. This takes place by means of circuits numbered one and two. Circuit number three, however, is broken at 40d, 41d, and no connection exists between the positive terminal of battery 27d and the entering end of the ramp *d*. Instead a circuit energizing the entering end of ramp *d* is established as follows:

Circuit number six

Starting with the entering end of ramp *d*,

conductor 36d, armature 37d and contact 38d of neutral polarized relay CHd, conductor 39d, polarized armature 40d and contact 44d of relay CHd, conductor 45d, negative terminal of battery 46d, positive terminal of battery 46d, contact 48d and polarized armature 49d of relay CHd, conductor 50d, contact 51d and armature 52d of relay CHd, and conductors 53d and 35d to the rail.

10 Neutral polar relay Hd receives its energization current from the battery Be and is energized in the same sense as relay H of the proceeding ramp e over a circuit that corresponds to circuit number four and the pole 70
15 changer armatures 20d, 30d are in the same position as the corresponding parts in block C.

While the relay Hd is energized in the same direction as the relay H it will be noted 20 however, that the energization of the relay CHd is reversed as compared with the direction of energization of the relay CH. The energization circuit for the relay CHd is as follows:

25 *Circuit number seven*

The negative terminal of the battery Bf, contact 75f, armature 62f of the relay Hf, the remainder of the circuit being the same 30 as the corresponding portion of circuit number five up to an inclusive of armature 72 of relay Hf, from which point the circuit is completed through the contact 76f and conductor 77f to the positive terminal of Bf.

35 The change in the direction of energization of the relay CHd, it will be seen, is due to the reversal of position of the pole changer consisting of the armatures 62f and 72f controlled by the relay Hf. Under the conditions indicated the source of energy for relay Hf has been cut off by the break in its circuit at the armature 67f and contact 66f controlled by the track relay TF. The latter is deenergized due to the presence of the train 40 45 a in the block F.

Energization of ramp for caution danger indication

Ramp e is disposed at the entrance into 50 the block E and shall, therefore, be energized in such a manner as to give a caution indication for the block E and a danger indication for the block F. In order to bring about such indications both ends of the ramp e are now 55 energized negatively. The battery 27e serves as a source for the application of negative energization to the leaving end of the ramp e. The circuit for accomplishing this end is as follows:

60 *Circuit number eight*

Commencing at the leaving end of ramp e, conductors 15e, 16e, armature 17e and contact 18e of relay He, conductor 19e, polarized 65 armature 20e and contact 54e of relay He,

conductor 28e, negative terminal of battery 27e, battery positive terminal, conductor 55e, contact 56e and polarized armature 30e, conductor 31e, contact 32e and armature 33e of relay He, and conductors 34e and 35e to the adjacent rail.

The entering end of ramp e is also connected to the negative terminal of battery 27e through the following circuit:

75 *Circuit number nine*

The entering end of ramp e, conductor 36e, armature 37e, and contact 57e, conductor 43e to conductor 16e and from this point the circuit follows circuit number eight.

On comparing the condition of the wiring system associated with the ramp e with that of ramp c, it will be observed that the pole changer 20e, 30e occupies the opposite position from that occupied by the corresponding elements in the circuits associated with ramp c. The same is true of the pole changer 40e, 49e as compared with the corresponding elements in the system associated with ramp c. The position of the pole changer 20e, 30e has been reversed because the direction of energization of the relay He has been reversed. The relay He is energized by the battery Bf through the following circuit:

90 *Circuit number ten*

The negative terminal of battery Bf, contact 75f and armature 62f of the relay Hf, the remainder of the circuit following the corresponding portion of circuit number four until the armature 72 is reached, from which point the circuit is completed through contact 76f and conductor 77f to the positive terminal of the battery.

The circuits numbered five and seven for the energization of the relay CHe, however, are broken at 66f, 67f, with the result that its armatures are in the positions indicated which makes it possible for the negative side of the battery 27e to be connected to the entering end of the ramp e through the armature 37e.

Deenergization of ramp to indicate danger

Ramp f is disposed at the entrance to the block F which is occupied. Under such conditions the operator is not concerned with the condition of the block ahead of F, and it is important that the operator should receive only a danger indication. Any indication at this point of the condition of the block ahead of F will only serve to confuse the operator. Under these conditions, therefore, the circuits are so designed that the ramp f is entirely deenergized. This is brought about by the deenergization of both relays Hf and CHf. The energization circuit of relay Hf is broken at 66f, 67f with the result that the circuit, which in the previous blocks serve

115
120
125
130

to connect the leaving end of the ramp and

- the battery 27, is broken at the point 17f, 18f and at the point 32f, 33f while the circuit, which in the previous blocks serves to connect the entering end of the ramp f to a source of energy is broken at the same point and at other points. Moreover, the circuit for the relay CHf is broken at the point of contact between the contact 3f and armature 2f which are controlled by the relay Hf.
- 10 It will thus be seen that by the aid of the roadside system described and disclosed herein in each ramp is capable of giving three pairs of indications for each of the two succeeding blocks, such signals being transmitted in the 15 desired combinations. In addition to these each ramp may give a seventh single danger indication, it being desired to transmit only a danger indication when the immediate block is occupied. The polarized armatures of the respective line relays H, CH, etc., remain in the positions into which the same are last moved until a definite disturbing impulse is received by said relays.

25 *Vehicle carried devices*

The shoe S carried by the vehicle is of a type well known in the art and is so constructed that as the shoe comes in contact with and rides over a ramp interposed in its path the shoe is moved upwardly from the position shown in Figure 1 to a position wherein the contact is broken between the bridging elements 262 and 271 and brush contacts 263 and 270 respectively. On the other hand, the same operation brings the bridging elements 262 and 271 into electrical contact with the brushes 133 and 85 respectively, prior to the disengagement of brushes 263 and 270 with 262 and 271 respectively. 40 The bridging elements 262 and 271 are mounted on the shank of the shoe S but are insulated therefrom.

The vehicle also carries an indication selector generally designated by the reference numeral I in the drawings which is more clearly described in the patent to Theodore Bodde, No. 1,527,465 of February 24, 1925. This indication selector comprises a starter ST and a rotor RO which is movable into any 45 one of three positions. The normal or clear position is indicated by the position p1; the reverse or caution position is indicated by the dotted line position p2 and the neutral or danger position is indicated by the dotted line position p3. Associated with the rotor element are three contact making and breaking elements 210, 106 and 127 which are also capable of assuming three positions which are indicated as p1, p2 and p3 to correspond 50 with the positions which the rotor RO is capable of assuming. The position p1 is assumed by the rotor and the enumerated contacts when the electromagnet ST is energized by a current of a positive polarity. 55 Position p2 is assumed by these rotatable

elements when the electromagnet ST is energized by a current of the reverse polarity and the position p3 is assumed when the starter receives no energy from the ramp and the holding magnet K is deenergized.

The starter magnet ST and the lock magnet LM of the indication selector I are arranged in series and the resistance R2 is connected in parallel therewith. The function of the resistance R2 is to slow up the drop away of the rotor RO whenever a momentary interruption occurs in the circuit of the starter magnet and of the lock magnet such as at the point of insulation between the ramp sections.

This multiple series circuit R2, LM—ST, is connected in a partial circuit to the shoe S and to the frame of the vehicle, represented by the ground connection G which may be traced as follows:

Circuit number eleven

Shoe S, conductor 213, magnet ST and lock magnet LM in parallel with resistance R2, and conductor 214 to ground. Whenever the shoe S rides over the ramps c, d, e and f the said partial circuit eleven will cooperate with a roadside partial circuit connected to these ramps, and to the adjacent rail as is disclosed in Fig. 2, and described more in detail hereinabove.

For holding or maintaining the rotor RO of indication selector I, and the make and break means 210, 106, and 127, in the positions to which these parts are actuated when the shoe moves over and off the ramp, the indication selector includes a holding circuit which is broken when the shoe moves over the ramp to permit freedom of action of the moving parts in response to energization of the 105 starter coil ST and also to destroy the indication received at the last indicating point, so that a new one, if present, may be picked up freely as just mentioned. This circuit is again closed when the shoe S disengages the 110 ramp.

The said holding means comprises an electro-magnet K having pole pieces p4 and p5, selectively operable for cooperating with the armature a', of rotor RO to hold the same in either the position p' or p2. The holding circuit may be traced as follows:

Circuit number twelve

Positive terminal of battery N, conductor 120 201, resistance R', conductors 202 and 260, contact 261, movable make and break member 262 and contact 263, of shoe S, conductors 264 and 265, magnet 266 of clutch K, conductors 267, 268 and 269, contact 270, movable make and break member 271, and contact 272 of shoe S, conductors 273, 274, 275 and 212 to negative terminal of battery N.

This circuit is normally closed, as traced, and when the shoe S engages a ramp, this cir- 130

cuit is broken at contacts 263 and 270 to effect the deenergization of the holding magnet 266 of clutch K thus permitting the freedom of motion and operation of the rotor RO. When 5 the shoe S leaves the ramp this circuit is again closed at the contacts 263 and 270, for reenergizing the holding magnet 266 of the clutch K of selector I to hold the armature a' in the position to which it has been operated by the 10 selective energization of the starter ST operating its rotor RO. If there is no energization of the starter ST due to the passage of shoe S over a deenergized ramp, then the armature a' will gravitate to the neutral position p_3 , and the lock NL will drop into a slot 15 on rotor RO which also gravitates to the neutral position.

Shoe S as heretofore mentioned picks up the roadside indications from the ramps. 20 These received indications operate the selector I which in turn controls the relays or magnets I' , I^2 RS and M as well as the cab signals BA. The selector I is shown in the clear running position, namely, in the position assumed by the selector whenever the shoe S passes over and leaves a positively energized ramp, even though the entering end 25 of the ramp may be energized negatively.

The contacts and armatures controlled by 30 the relays I' and I^2 are also shown in the clear running position, and as shown in Figure 1 correspond to the position assumed by such contacts whenever the shoe S passes over a ramp having both ends energized positively 35 such as ramp c. Under such conditions the cab signals are green green.

For the purpose of obviating unnecessary repetition, the partial circuit connecting the negative terminal of the battery N to the common return for all the signal circuits may be 40 traced as follows, and hereafter it will be sufficient to trace the partial circuit from the positive terminals of battery N to the respective signals:

45 Circuit number thirteen

Common return of signals BA, conductors 110, 83, 84, 269, contact 270, bridging element 271 on shoe S, contact 272, conductors 273, 50 274, 275 and 212 to the negative terminal of the battery N.

The signals under column B indicate the condition of the immediate block and those under column A indicate the condition of the 55 block next ahead.

The circuit of the green signal G under B is completed by the following:

Circuit number fourteen

60 Positive terminal of battery N, conductor 201, resistance R' , conductors 202, 260, contacts 261, bridging element 262 on shoe S, contact 263, conductors 264 and 105, movable member 106, and contact 107, and conductors 65 108 and 109 to the green cab signal under B.

The completion of the circuit of the green signal under A may be traced as follows:

Circuit number fifteen

This circuit follows circuit number fourteen up to and including conductor 108 and from this point proceeds along conductor 111, armature 112 of relay I^2 , contact 113, and conductor 114 to the green signal under A. 70

Operation of vehicle carried system on passing ramp d

Coming back to the traffic conditions illustrated in the drawings let us observe the series of operations that take place when the train b passes over and leaves ramp d. It is to be remembered that the vehicle carried circuits are now in the condition illustrated in Figure 1 for the reason that the train had just 80 passed the ramp c which was energized positively at each end. When the shoe S comes in contact with the entering end of the ramp d, the shoe is raised with the result that the circuit twelve of the holding magnet 266 for the clutch K is broken at 270 and 263. The rotor RO of the selector I is free to be rotated to any position depending upon the indication existing on the entering end of the ramp d. The rotor RO is so constructed that when the magnetic clutch K is deenergized, the rotor will swing back to its intermediate position indicated by p_3 and with it the armatures 210, 106, 127 will also be moved to their p_3 positions. The two green cab signals will, therefore, become deenergized and will serve as an indication to the operator that the train is passing a ramp. 90

The release of the magnetic clutch permits the starter magnet ST to rotate the rotor RO in a direction depending upon the manner of energization of the entering end of the ramp d. In the present instance, the entering end of the ramp d is energized negatively. 95

The current flowing from the ramp 100 through the starting magnet ST and the lock magnet LM to the rail through the ground connection will, therefore, serve to rotate the rotor into the p_2 position. This brings about the energization of the relay I' through the following circuit:

Circuit number sixteen

Positive terminal of the battery N, conductor 120, resistance R' , conductor 126, movable contact member 127 in its p_2 position, contact 128, conductors 129 and 130, magnet 131 of relay I' , conductors 132, 274, 275 and 212 to the negative terminal of the battery N. 120

Now if a ramp is energized negatively at both ends then relay I' will remain energized by circuit sixteen after the shoe S leaves the ramp for the reason that RO remains in its p_2 position. If, however, a ramp is encountered, which is energized negatively on the 125 130

entering end and positively on the leaving end, such as ramp *d*, then circuit sixteen is broken as soon as the shoe comes in contact with the leaving end of the ramp, for the positive energization of the leaving end of the ramp, causes the rotor RO and its contacts to move back to the *p1* position. Before this happens, however, the following stick circuit for *I'* is established:

10

Circuit number seventeen

Positive terminal of battery N, conductor 201, resistance *R'*, conductors 202, 260, brush 261, bridging element 262, contact 133, conductor 134, armature 135, contact 136, conductors 137, 130, winding 131, conductors 132, 274, 275, 212 to the negative terminal of the battery N.

The stick circuit seventeen it will be seen eliminates the movable contact 127 and substitutes therefor the shoe control bridging element with the brushes 61 and 133. The relay *I'* will therefore remain energized as long as the shoe remains in its raised position regardless of the manner in which the leaving end of the ramp is energized. When the shoe *S* enters upon the leaving end of the ramp *d*, the indicator *I* receives energy flowing in the direction from the shoe to the ground and it will operate the rotor back to the position *p'* as well as the movable contacts associated with the rotor. When shoe *S* leaves the ramp and movable member 262 of the shoe disengages the contact 133, the stick circuit seventeen of the relay *I'* is opened and the relay is deenergized. Before this happens, however, relay *I²* is energized through the following circuit:

10

Circuit number eighteen

Positive terminal of battery N, conductor 201, resistance *R'*, conductors 202, 260, contacts 261, 263, bridged by movable member 262 of the shoe *S* as it descends and just before this movable member 262 disengages contact 133, conductors 264, 105, movable contact 106 and contact 107, conductor 138, magnet 139 of relay *I²*, conductors 140, 141, contact 142 and armature 143 of relay *I'*, conductors 144, 275 and 212 to negative terminal of battery N.

Since this circuit includes armature 143 of relay *I'*, it will be opened as soon as the shoe leaves the ramp, because relay *I'* then becomes deenergized. A stick circuit is therefore provided for relay *I²* which may be traced as follows:

Circuit number nineteen

From the positive terminal of the battery N the circuit follows circuit eighteen up to and including conductor 140 and from this point the circuit may be traced as follows: conductor 145, armature 146 and contact 147 of relay *I²*, conductors 148, 268, 269, contacts

270 and 272 bridged by the bridging movable element 271, conductors 273, 274, 275 and 212 back to the negative terminal of the battery N.

The circuit just traced goes into effect immediately after circuit eighteen is completed and serves to hold the relay *I²* in its energized condition even though *I'* has become deenergized by the opening of its stick circuit at the point 133 when the shoe descends. The resultant effect of the series of operations which took place when the shoe *S* passed over the ramp *d* was to leave the rotatable element RO with its movable contacts in the positions shown in Figure 1 but to leave the relay *I²* energized with the resultant attraction of the armatures 112 and 146. This brings about an operation of the green cab signal under B and the yellow cab signal under A. The green cab signal under B is energized through circuit fourteen which although broken temporarily is restored before the shoe descends from the ramp.

At the same time the energizing circuit for the yellow A signal is established as follows:

Circuit number twenty

This circuit for the yellow A signal is the same as circuit fifteen for the green A signal as far as the armature 112 of relay *I²*. Relay *I²* now being energized armature 112 is closed against contact 115, circuit 15 is broken and the circuit for yellow A is completed as follows: contact 115, conductor 116 to the yellow signal Y under A.

As the train proceeds in the block *d* the stick circuit eighteen of the relay *I²* maintains the green signal under B and the yellow A signal in energized state until the train reaches the position where the shoe *S* strikes the ramp *e* which is energized negatively at both ends.

At this point the clutch magnet K is again released and the relay *I²* is deenergized due to the break in its stick circuit at the point 270 caused by the upward movement of the shoe *S*. The starter magnet ST of the selector I receives a negative impulse and operates the rotor and its movable contacts to their *p2* positions and the circuits for the previously existing signals are broken. Relay *I'* becomes energized by circuit sixteen. In view of the fact that the leaving end of the ramp is also negatively energized the rotor of the indication selector will remain in its *p2* position, the relay *I²* will remain deenergized while the relay *I'* will remain energized after the shoe leaves the ramp *e*.

The closing of all the armatures controlled by the relay *I'* will energize the yellow B signal and the red A signal.

Circuit number twenty-one

The yellow B signal is energized by the

circuit which follows circuit fourteen up to and including armature 106 of selector I and from this point proceeds to contact 117 (106 being in its *p2* position) and conductor 118 and 119 to yellow B signal.

Circuit number twenty-two

The red A signal is energized by a circuit which follows circuit number twenty-one to 10 and including conductor 118. The relay I' being energized the circuit follows to conductor 120, contact 121 and armature 122 of relay I' and conductor 123 to red A signal.

The two signals indicated in Figure 7 will 15 remain energized as long as the train remains in block D. As the train approaches the ramp *f* and the shoe S comes in contact with the ramp *f* the clutch magnet K will again be released and the rotor will assume its *p3* position. In view of the fact that the ramp *f* is entirely deenergized the rotor will remain 20 locked in its *p3* position by the engagement of the neutral lock NL with the recess in the rotor. Under these conditions the only signal 25 that will be energized will be the red B signal whose circuit may be traced as follows:

Circuit number twenty-three

30 This circuit follows circuit number fourteen up to and including armature 106 which now is in its *p3* position and the circuit proceeds from contact 106 to contact 124 and conductor 125 to the red B signal.

35 All the other signal circuits are open and remain open as long as the train remains in block F.

Operation of the train control system

40 The train control system disclosed herein is in its substantial elements and manner of operation identical with the system disclosed in the Patent No. 1,513,562. In the present system, the train control elements and circuits 45 are combined with the cab signalling system disclosed herein and are designed to cooperate with ramps which indicate the condition of the immediate block and of the block next ahead. The circuits shown herein are therefore so arranged that the train control elements are responsive only to the condition of the immediate block.

50 In the train control system of my present invention for directly controlling the movement of the train there is provided an electrically operated device for controlling the operation of the air brake system. The device is under the control of cooperating train and roadside mechanism and is operated 55 thereby in accordance with roadside conditions as outlined, hereinbefore. This mentioned, electrically operated device comprises, in the preferred construction, an electro-magnet M, Figure 1, which controls the operation 60 of a combined reservoir and brake valve of the

type disclosed in the patent to A. G. Shaver No. 1,411,526 of April 4, 1922, and in the patent to Allen B. Kendall, 1,540,017 of June 2, 1925, the said reservoir and brake valve functioning upon the deenergization of the electro-magnet M for cutting off the supply of air from the main reservoir of the air brake system to the engineman's brake valve and for opening the train pipe to exhaust. Normally, the electro-magnet M is energized to hold open the communication between the main reservoir and the engineman's brake valve and to close the train pipe to exhaust.

The train also carries a reset magnet RS, 80 the winding of the magnet RS being connected in parallel with the magnet M, and the circuits of both passing through armatures controlled by the magnet RS. The magnet M therefore cannot be energized unless the magnet RS is energized. The armatures of the magnet RS are provided with a manual non-sticking device P' which when operated closes the circuits of RS and M and under proper conditions they will remain energized. The train is also provided with 85 a speed control device SC.

For normally controlling the operation of the electro-magnet M there is provided a train carried circuit which is normally energized as under "clear" roadside conditions 90 by a train carried source of energy such as battery N.

Circuit number twenty-four

This circuit may be traced as follows: 100 Positive terminal of battery N, conductor 201, resistance R', conductors 202 and 203, movable make and break means 204 of RS which is held in the closed position shown by the energized magnet of RS hereinafter described, contact 205, of this means, conductor 206, the electro-magnet M, conductors 207, 208 and 209, movable make and break indicating means 210 which is in its *p1* position under clear conditions, as hereinbefore described, the contact 211, conductor 212 to the negative terminal of battery N.

Under the "normal" or "clear" conditions the brake controlling magnet is energized 115 to permit the vehicle to proceed, and as explained before, this is the condition that prevails whenever shoe S leaves a ramp energized positively even though the entering end of the ramp is negative. The circuit controlling this valve magnet M for the other positions of the indication selector I will be described hereinafter.

Circuit number twenty-five

The reset magnet is normally energized 125 through the following circuit: This circuit follows circuit twenty-four up to and including conductor 203 and then follows conductor 95, armature 96, contact 97, conductors 98, 99, winding of magnet RS, con-

ductors 100, 101, and conductor 209, from which point it is completed in the same manner as circuit twenty-four. Whenever shoe S leaves a ramp energized negatively at its 5 leaving end, as explained hereinabove, the selector I remains in its p_2 position and the relay I' remains energized. These are the conditions that exist when a train is entering a caution block. The train under such 10 conditions should not exceed a predetermined medium speed. Assume that the train or vehicle is operating below the medium rate so that the contacts 279 and 81 of the speed controller SC are in contact 15 with its movable member 80. A medium speed control circuit for magnet M is established which may be traced as follows:

Circuit number twenty-six

20 Positive terminal of battery N, conductor 201, resistance R' , conductors 202, 203, movable member 204 and contact 205 of release switch RS conductor 206, magnet M of brake valve, conductors 207, 208, 209, movable 25 member 210 of selector I reversed to position p_2 , contact 276 of selector I, conductors 277 and 278, medium speed contact 279, closed to movable member 80 of speed controller SC, contact 81, conductors 82, 83, 84 30 and 269, contact 270 and movable member 271 of shoe S, contact 272, conductors 273, 274, 275 and 212 to negative terminal of battery N.

It will be noted that this medium speed 35 control circuit includes contact 270, movable member 271 and contact 272 of shoe S. It would appear, therefore, that the movement of shoe S upward in passing over a ramp, as for example ramp e , would open the magnet M circuit causing a deenergization of the magnet M. To prevent deenergization and avoid the necessity of closing switch P when passing over caution ramps and thus 40 avoid an automatic application of the brakes, 45 I have included an auxiliary or holding circuit, with the shoe up, so that the magnet M receives negative battery as follows:

Circuit number twenty-seven

50 This circuit follows circuit twenty-six through the magnet M to and including the conductor 207 and from this point is completed as follows: conductors 208, 209, armature 210 in its p_2 position, contact 276, conductor 277, contact 88 and armature 87 of energized relay I' , conductor 86, brushes 85 and 272 bridged by 271 of shoe S, conductors 273, 274, 275 and 212 to negative terminal of battery N.

55 When the shoe S is down, however, it will be noted that this circuit is open at contact 85 of shoe S and the only other circuit from the magnet M to the negative terminal of battery N when the speed is at or below the medium rate and above the low rate, is

through the speed controller SC, contacts 279 and 81, closed by the movable member 80, and through contacts 270 and 272 of shoe S closed by the movable member 271.

I shall now describe the circuit to magnet M for the occupied block, or deenergized position of selector I. In this case the selector I is in the position p_3 ; relays I' and I'' are deenergized; release switch RS is energized and the speed of the train is assumed to be at or below the low rate. The low speed circuit to magnet M may therefore be traced as follows:

Circuit number twenty-eight

This circuit follows circuit twenty-six through the magnet M and conductor 207 and from this point passes by way of conductor 89, contacts 90 and 81, bridged by speed controller movable member 80 to conductor 82 from which point it is completed in the same manner as circuit 26 through the shoe S.

It will be noted that this circuit passes through contacts 270 and 272 of shoe S, and when shoe S is up, contact 270 is out of contact with movable member 271, so in order to avoid deenergization of magnet M when shoe S is moved up by its passage over a deenergized ramp such as f , I have provided an auxiliary or holding circuit through the switch P to the negative terminal of battery N as follows:

Circuit number twenty-nine

Negative terminal of battery N, conductors 100 212, 275, 274 and 91, movable member 92 and contact 93 of switch P, conductors 94, 83, and 82, contacts 81 and 90 of speed controller SC closed by the movable member 80, conductors 89 and 207 to magnet M.

The circuits for controlling the valve magnet M as described for all three positions of the selector I, also control the release switch RS since the magnet of RS receives its energy over these circuits.

It will be noted that the release switch RS is controlled through its movable member 96, so that magnet RS can only be energized when this member 96 is closed to the contact 97, providing the balance of the control circuit is complete. Whenever magnet RS is deenergized due to the opening of its circuit at the speed controller SC or at shoe S when switch P is open, then the movable members 204 and 96 of RS drop and remain in the deenergized position until restored to the normal or up position by manually operating the impulse button P'. Whenever RS is deenergized as just described, the circuit controlling the valve magnet M is open at contact 205 and movable member 204 of RS. The opening of this circuit causes a deenergization of magnet M which in turn brings about an automatic application of the brakes to bring the train to a halt unless the operator of the ve- 130

hicle becomes alert to operate the impulse button P' when the speed is right. The operator is advised when he may operate this button P' by the indication received through the signal or light L of RS. This signal is displayed only when RS is deenergized and the speed is below the prescribed medium or low rate as the case may be. The circuit for this signal L is as follows:

10 *Circuit number thirty*

Positive energy in conductors 203 and 95 as before, movable member 96 of RS closed to contact 102, conductor 103, signal L, conductor 104, to conductor 101, which is energized negatively, through conductor 209 for both positions p_3 and p_2 of movable member 210 of selector I. When member 210 is in position p_2 the signal L of RS receives negative energy through the medium speed contact 279 of speed controller SC, and when member 210 of selector I is in position p_3 , then signal L of RS receives negative energy through conductors 208, 89 and low speed contact 90 of speed controller SC.

The release switch RS is made slow acting so that it will not open its contacts during the very small space of time it takes for member 210 of the selector I to operate from position p_1 to p_2 . This is done to avoid an automatic application of the brakes when entering caution blocks at or below the medium speed. The resistance R_3 of RS stimulates the slow acting feature of RS whenever a momentary opening of its circuit occurs. The impulse button P' may be of any desired type and may be separate from the release switch RS two-contact relay. I prefer, however, to use the stick release switch combined with the impulse button as shown, and as disclosed in the application of Archibald G. Shaver, Ser. No. 634,053 of April 28, 1923.

The operation of the train control system may be briefly summarized as follows:

45 The brake valve magnet M and the reset magnet RS are normally energized by circuits twenty-four and twenty-five respectively which include the contact 210 of the selector I in its p_1 position. When on entering block D, the selector I is temporarily in its p_2 position circuit number twenty-seven serves in place of circuits twenty-four and twenty-five. An automatic application of the brakes under such conditions is thereby prevented, and the train remains free to enter and proceed in block at the maximum permissible speed.

When the train is about to enter the caution block E and the shoe S comes in contact with ramp e, the selector I will assume the p_2 position and will remain in that position throughout the train's progress in block E. Circuit number twenty seven maintains the magnets M and RS energized as long as the shoe is on the ramp. When the shoe leaves

the ramp the magnets may obtain their energization only through circuit number twenty-six. As soon, therefore, as the train exceeds the medium permissive speed, magnets M and RS become deenergized, contacts 96 and 204 assume their open circuit positions and the brakes are applied. If the operator wishes to proceed he must operate the nonstick pushbutton P', after the signal L has indicated that the train has reached the medium permissive speed. When P' is operated under such conditions circuit 26 is reestablished and the train is again under the joint control of the operator and the automatic control system.

As the train proceeds and is about to enter the occupied block F, the contact of the shoe S with the deenergized ramp f will put I in its p_3 position. If the operator wishes to enter the block against the danger signal he must reduce his speed to the low permissive speed and must hold switch P closed as the shoe rides over ramp f. When the train has entered the occupied block, the train is again under the joint control of the operator and the automatic system and when the train exceeds the low permissive speed, the brakes are applied.

I claim:

1. A railway cab signalling system comprising a set of cab signals to indicate the traffic condition of the immediate block, a separate set of cab signals to indicate the traffic condition of the block next ahead, train carried means for said sets of cab signals, and wayside means arranged at spaced control stations cooperating with said train carried means to selectively operate said signals in accordance with traffic conditions, said train carried means including a circuit network having means to produce persisting electrical indications corresponding to the operation of said wayside means.

2. A railway cab signalling system comprising a plurality of cab signals to indicate the traffic conditions of the immediate block, a plurality of cab signals to indicate the traffic conditions of the block next ahead, train carried means and wayside means for selectively operating said signals in accordance with traffic conditions, said wayside means comprising a plurality of roadside elements arranged in each block, and circuit means for producing any one of three indications in each of said roadside elements of the block responsive to the traffic conditions of the immediate block and the traffic conditions of the block next ahead.

3. A railway cab signalling system comprising a plurality of cab signals to indicate the traffic conditions of the immediate block, a plurality of cab signals to indicate the traffic conditions of the block next ahead, train carried means and wayside means for selectively operating said signals in accordance

with traffic conditions, said wayside means comprising a plurality of roadside elements arranged in each block, and circuit means for producing any one of three indications 5 in each of said roadside elements of the block responsive to the traffic conditions of the immediate block and the traffic conditions of the block next ahead, the indications produced in said roadside elements of a block 10 being differently controlled by said circuits.

4. A railway cab signalling system comprising a set of cab signals to indicate the traffic conditions of the immediate block, a separate set of cab signals to indicate the traffic 15 conditions of the block next ahead, train carried means and wayside means operative for selectively controlling said signals in accordance with traffic conditions, said wayside means comprising for each block a plurality 20 of roadside elements, a system of circuits associated with one of said roadside elements and a separate system of circuits associated with the other of said roadside elements, said circuit systems being operative for energizing 25 each of said roadside elements with different energy characteristics.

5. A railway cab signalling system comprising a set of cab signals to indicate the traffic conditions of the immediate block, a separate set of cab signals to indicate the traffic conditions of the block next ahead, train carried means and wayside means operative for selectively controlling said signals in accordance with traffic conditions, said wayside means comprising for each block a plurality 30 of roadside elements, a system of circuits associated with one of said roadside elements and a separate system of circuits associated with the other of said roadside elements, said circuit systems being operative for selectively energizing each of said roadside elements negatively or positively.

6. A railway cab signalling system comprising a set of cab signals to indicate the traffic conditions of the immediate block, a separate set of cab signals to indicate the traffic conditions of the block next ahead, train carried means and wayside means operative for selectively controlling said signals 45 in accordance with traffic conditions, said wayside means comprising for each block a plurality of roadside elements, a system of circuits associated with one of said roadside elements and a separate system of circuits associated with the other of said roadside elements, said circuit systems being operative for energizing each of said roadside elements negatively or positively or for deenergizing 50 the same.

7. In a railway cab signalling system, a roadside system adapted to cooperate with train carried devices comprising for each block an electro responsive device, circuit means associated with the electro responsive device responsive to the traffic conditions of 60

the immediate block, another electro responsive device, and circuit means associated therewith responsive to the traffic conditions of the block next ahead, a signalling roadside ramp having different sections, each in a partial electrical circuit adapted to be completed by cab carried circuits, interposed in the path of the train to cooperate with train carried devices, and means whereby each of said different sections of said ramp is variably energized with positive and negative potentials to give indications in accordance with the condition of the said circuits. 70 75

8. In a railway cab signalling system, a roadside system comprising a two part roadside element interposed in the path of the train to cooperate with train carried devices, a partial electrical circuit adapted to be completed by a cab carried circuit associated with each part of said element for varying the character of energy delivered to each part of said element, an electro responsive device variably responsive to the traffic conditions of the immediate block for controlling the circuit means associated with one part of said roadside element, and another electro responsive device variably responsive to the traffic conditions of the block next ahead for controlling the circuit means associated with the other part of said roadside element. 80 85 90

9. In a railway cab signalling system, a roadside system comprising for a given block a two part roadside ramp interposed in the path of the train to cooperate with train carried devices, a partial electrical circuit adapted to be completed by a cab carried circuit associated with each part of said ramp for varying the polarity on each part of said ramp, an electro responsive device variably responsive to the traffic conditions of the immediate block for controlling the circuit means associated with one part of said roadside ramp, another electro responsive device variably responsive to the traffic conditions of the block next ahead for controlling the circuit means associated with the other part of said roadside ramp, and separate energy sources for said electro responsive devices. 100 105 110

10. In a railway cab signalling system, a roadside system, comprising an electro responsive device adapted to assume three conditions, means associated with said device and with the immediate block whereby said device is put selectively into any one of said three conditions in accordance with the traffic condition of the block, another electro responsive device capable of assuming any one of three conditions, means associated with said last named electro responsive device and with the block next ahead for putting selectively said last named device in any one of the three conditions in accordance with the traffic condition of the block next ahead, a two part roadside element in said immediate block interposed in the path of the train to co- 115 120 125 130

operate with train carried devices and circuit means associated with said element and controlled by said electro responsive devices whereby each part of said element may give a 5 separate indication.

11. In a railway cab signalling system, a roadside system, comprising an electro responsive device adapted to assume three conditions, means associated with said device 10 and with the immediate block whereby said device is put selectively into any one of said three conditions in accordance with the traffic condition of the block, another electro responsive device capable of assuming any 15 one of three conditions, means associated with said last named electro responsive device and with the block next ahead for putting selectively said last named device in any one of the three conditions in accordance with 20 the traffic condition of the block next ahead, a two part roadside ramp in said immediate block interposed in the path of the train to cooperate with train carried devices and circuit means associated with said ramp and 25 controlled by said electro responsive devices whereby each part of said ramp may give a separate indication.

12. In a railway cab signalling system, comprising a track divided into a series of 20 insulated blocks, a roadside system comprising a two part roadside element disposed at the entrance to each block in the path of travel of the train to cooperate with the train carried devices, a partial circuit for each part 25 of said roadside element adapted to be completed by a cab carried circuit and means for variably energizing one part of said element with different energy characteristics in accordance with the condition of the immediate 30 block and for variably energizing the other part of said element with different energy characteristics in accordance with the condition of the block next ahead.

13. In a railway cab signalling system, comprising a track divided into a series of 45 insulated blocks, a roadside system comprising a two part roadside ramp disposed at the entrance to each block in the path of travel of the train to cooperate with the train carried devices, a partial circuit for each part 50 of said roadside element adapted to be completed by a cab carried circuit and means for variably energizing one part of said ramp with different energy characteristics in accordance with the condition of the immediate 55 block and for variably energizing the other part of said ramp with different energy characteristics in accordance with the condition of the block next ahead.

14. In a railway cab signalling system, comprising a track divided into a series of 60 insulated blocks, a pair of roadside elements disposed adjacent the entrance to each of said blocks in the path of approaching trains, a wiring system associated with each of said 65

pair of elements, an electro responsive device in each of said systems and circuit means associated therewith for controlling the energization of one of said elements, another electro responsive device and circuit means 70 associated therewith for separately controlling the energization of the other of said elements, a source of energy associated with each of said wiring systems and means whereby said source of energy may be connected 75 to the first mentioned electro responsive device of the block immediately preceding and to the second electro responsive device of the block next preceding.

15. In a railway cab signalling system, 80 comprising a track divided into a series of insulated blocks, a pair of roadside ramps disposed adjacent the entrance to each of said blocks in the path of approaching trains, a wiring system associated with each of said 85 pair of ramps, an electro responsive device in each of said systems and circuit means associated therewith for controlling the energization of one of said ramps, another electro responsive device and circuit means associated 90 therewith for separately controlling the energization of the other of said ramps, a source of energy associated with each of said wiring systems and means whereby said source of energy may be connected to the first 95 mentioned electro responsive device of the block immediately preceding and to the second electro responsive device of the block next preceding.

16. In a railway cab signalling system comprising a track having a series of insulated blocks, a pair of roadside elements disposed at the entrance to each block in the path of an approaching train and adapted to cooperate with a train carried device, a wiring system associated with each pair of said roadside elements, each of said wiring systems including an electro responsive device and circuits associated therewith for variably controlling the energization of one of 100 said pair of elements and another electro responsive device and circuits associated therewith for variably and separately controlling the energization of the other of said 105 pair of elements, a source of energy in each of said wiring systems, and means controlled by the first of said electro responsive devices whereby said source of energy may be variably connected to the first electro responsive device of the block immediately preceding 110 and to the second electro responsive device of the block next preceding.

17. In a railway cab signalling system comprising a track having a series of insulated blocks, a pair of roadside ramps disposed at the entrance to each block in the path of an approaching train and adapted to cooperate with a train carried device, a wiring system associated with each pair of said 115 roadside ramps, each of said systems includ- 120

- ing an electro responsive device and circuits associated therewith for variably controlling the energization of one of said pair of ramps and another electro responsive device and 5 circuits associated therewith for variably and separately controlling the energization of the other of said pair of ramps, a source of energy in each of said wiring systems, and means controlled by the first of said electro responsive devices whereby said source of energy may be variably connected to the first electro responsive device of the block immediately preceding and the second electro responsive device 70 of the block next preceding.
- 10 20 25 30 35 40 45 50 55 60 65 70 75 80 85 90 95 100 105 110 115 120 125 130
18. In a railway cab signalling system comprising a track divided into a series of insulated blocks, a roadside system comprising a roadside element disposed at the entrance to each block in the path of approaching trains for indicating the traffic condition of the immediate block, another roadside element disposed at the entrance to each block for indicating the traffic condition of the block next ahead, said roadside elements being disposed on the same side of the track to cooperate with a train carried device, a wiring system associated with each pair of said roadside elements, each of said wiring systems including an electro responsive device and circuits associated therewith for variably controlling the energization of one of said pair of elements and another electro responsive device and circuits associated therewith for variably controlling the energization of the other of said pair of elements, a source of energy in each of said wiring systems, and means controlled by the first of said electro responsive devices whereby said source of energy may be variably connected to the first electro responsive device of the block immediately preceding and the second electro responsive device of the block next preceding.
18. In a railway cab signalling system comprising a track divided into a series of insulated blocks, a roadside system comprising a roadside ramp disposed at the entrance to each block in the path of approaching trains for indicating the traffic condition of the immediate block, another roadside ramp disposed at the entrance to each block for indicating the traffic condition of the block next ahead, said roadside ramps being disposed on the same side of the track and one in advance of the other to cooperate with a train carried device, a wiring system associated with each pair of said roadside ramps, each of said wiring systems including an electro responsive device and circuits associated therewith for variably controlling the energization of one of said pair of elements and another electro responsive device and circuits associated therewith for variably controlling the energization of the other of said pair of elements, a source of energy in each of said wiring systems, and means controlled by the first of said electro responsive devices whereby said source of energy may be variably connected to the first electro responsive device of the block immediately preceding and the second electro responsive device of the block next preceding.
20. In a railway cab signalling system comprising a track divided into a series of insulated blocks, a roadside system comprising a roadside element disposed at the entrance to each block in a path of approaching trains for indicating the traffic condition of the immediate block, another roadside element disposed at the entrance to each block for indicating the traffic condition of the block next ahead, said roadside elements being disposed on the same side of the track and one in advance of the other to cooperate with a train carried device, a wiring system associated with each pair of said roadside elements, each of said wiring systems including an electro responsive device and circuits associated therewith for variably controlling the energization of one of said pair of elements and another electro responsive device and circuits associated therewith for variably controlling the energization of the other of said pair of elements, a source of energy in each of said wiring systems, and means controlled by the first of said electro responsive devices whereby said source of energy may be variably connected to the first electro responsive device of the block immediately preceding and the second electro responsive device of the block next preceding.
20. In a railway cab signalling system comprising a track divided into a series of insulated blocks, a roadside system comprising a roadside ramp disposed at the entrance to each block in a path of approaching trains for indicating the traffic condition of the immediate block, another roadside ramp disposed at the entrance to each block for indicating the traffic condition of the block next ahead, said roadside ramps being disposed on the same side of the track and one in advance of the other to cooperate with a train carried device, a wiring system associated with each pair of said roadside ramps, each of said wiring systems including an electro responsive device and circuits associated therewith for variably controlling the energization of one of said pair of elements and another electro responsive device and circuits associated therewith for variably controlling the energization of the other of said pair of elements, a source of energy in each of said wiring systems, and means controlled by the first of said electro responsive devices whereby said source of energy may be variably connected to the first electro responsive device of the block immediately preceding and the second electro responsive device of the block next preceding.

22. In a railway cab signalling system, a train carried system comprising a train carried device cooperating with a roadside device for picking up roadside indications, one set of signals for indicating the traffic condition of the immediate block, another and a separate set of signals for indicating the traffic condition of the block next ahead and selective means operating through said train carried and roadside devices for energizing said signals in pairs, said selective means including a train carried circuit network operative to produce persisting electrical indications corresponding to the roadside indications picked up by said train carried device. 70
23. In a railway cab signalling system, a train carried system comprising a train carried contact shoe cooperating with a roadside ramp for picking up different energy characteristics corresponding to a roadside indication, one set of signals for indicating the traffic condition of the immediate block, another and a separate set of signals for indicating the traffic condition of the block next ahead and selective means operating through said shoe and ramp for energizing said signals in pairs, said selective means including the train carried circuit network operative to produce persisting electrical indications corresponding to the roadside indications picked up by said shoe. 75
24. A railway cab signalling system comprising a track divided into insulated blocks, a roadside element disposed at the entrance to each block in the path of an approaching train, roadside means whereby each of said elements may transmit two impulses to the train carried system, a train carried device cooperating with said roadside element for picking up said impulses, a group of signals carried by said train to indicate the condition of the immediate block, another and different group of signals carried by said train to indicate the condition of the block next ahead and vehicle carried selective means responsive to the pair of impulses for energizing the signals in predetermined pairs, one from each group. 80
25. A railway cab signalling system comprising a track divided into insulated blocks, a roadside ramp disposed at the entrance to each block in the path of an approaching train, roadside means whereby each of said ramps may transmit two impulses to the train carried system, a train carried contact shoe cooperating with said roadside ramp for picking up said impulses, a group of signals carried by said train to indicate the condition of the immediate block, another and different group of signals carried by said train to indicate the condition of the block next ahead and vehicle carried selective means responsive to the pair of impulses for energizing the signals in predetermined pairs, one from each group, said selective means including a train carried circuit network operative to produce persisting electrical indications corresponding to the roadside indications picked up by said train carried device. 85
26. A railway cab signalling system for giving separate indication to the operator of the condition of the immediate block and of the block next ahead comprising a roadside system and a cooperating train carried system, means in said roadside system for transmitting a plurality of pairs of impulses to said train carried system, a train carried device for picking up said impulses, a group of signals on said train for indicating the condition of the immediate block, another and different group of signals on said train for indicating the condition of the block next ahead and means whereby said signals are selectively actuated by said impulses in pairs, one from each group, said selective means including a train carried circuit network operative to produce persisting electrical indications corresponding to the roadside indications picked up by said train carried device. 90
27. A railway cab signalling system comprising a roadside system for transmitting a variable pair of impulses one of said impulses being variable in accordance with the traffic condition of the immediate block and the other of said impulses being variable in accordance with the traffic condition of the block next ahead, and a train carried system comprising a device for picking up said impulses, a three position selector actuated by said impulses, a pair of relays, a group of signals on the cab for the immediate block and another group of signals on the cab for the block next ahead. 95
28. In a combined train control and cab signalling system of the type having a roadside device to transmit variable pairs of impulses to a vehicle carried system, one impulse of the pair being for the condition of the immediate block and another impulse of the pair for the condition of the block ahead, a vehicle carried device for picking up such impulses, a selector responsive to said impulses, a train control relay, a normally closed circuit for said relay controlled by said selector, and an auxiliary circuit for said relay effective when the vehicle carried device is passing over said roadside device. 100
29. In a cab signalling system, the combination of a two part roadside element, means for imparting to one part an indication of the condition of the block next ahead and to the other part an indication of the condition of the immediate block, a train carried device passing over said parts in quick succession, separate train control signals, and means for energizing one of said signals when said device is passing over one part and for energizing another of said signals when said device 105
30. In a cab signalling system, the combination of a two part roadside element, means for imparting to one part an indication of the condition of the block next ahead and to the other part an indication of the condition of the immediate block, a train carried device passing over said parts in quick succession, separate train control signals, and means for energizing one of said signals when said device is passing over one part and for energizing another of said signals when said device 110
31. In a cab signalling system, the combination of a two part roadside element, means for imparting to one part an indication of the condition of the block next ahead and to the other part an indication of the condition of the immediate block, a train carried device passing over said parts in quick succession, separate train control signals, and means for energizing one of said signals when said device is passing over one part and for energizing another of said signals when said device 115
32. In a cab signalling system, the combination of a two part roadside element, means for imparting to one part an indication of the condition of the block next ahead and to the other part an indication of the condition of the immediate block, a train carried device passing over said parts in quick succession, separate train control signals, and means for energizing one of said signals when said device is passing over one part and for energizing another of said signals when said device 120
33. In a cab signalling system, the combination of a two part roadside element, means for imparting to one part an indication of the condition of the block next ahead and to the other part an indication of the condition of the immediate block, a train carried device passing over said parts in quick succession, separate train control signals, and means for energizing one of said signals when said device is passing over one part and for energizing another of said signals when said device 125
34. In a cab signalling system, the combination of a two part roadside element, means for imparting to one part an indication of the condition of the block next ahead and to the other part an indication of the condition of the immediate block, a train carried device passing over said parts in quick succession, separate train control signals, and means for energizing one of said signals when said device is passing over one part and for energizing another of said signals when said device 130

passes over said second part, said energizing means including a circuit network operative to produce persisting energization of said signals while the train moves between road-side elements.

30. In a cab signalling system, the combination of a two part roadside ramp, means for imparting to one part an indication of the condition of the block next ahead and to the other part an indication of the condition of the immediate block, a train carried device passing over said parts in quick succession, separate train control signals, and means for energizing one of said signals 70
- 10 when said device is passing over one part and for energizing another of said signals when said device passes over said second part, said energizing means including a circuit network operative to produce persisting energization 80
- 15 of said signals as the train moves between ramps. 85

31. In a cab signalling system, the combination of a two part roadside element, means for imparting to one part an indication of the condition of the block next ahead and to the other part an indication of the condition of the immediate block, a train carried device passing over said parts in quick succession, separate train control signals, and 90
- 25 means for energizing one of said signals when said device is passing over one part and for energizing another of said signals when said device passes over said second part, said last named means also serving to maintain said 95
- 30 signals energized until the train encounters another roadside element. 100

32. In a cab signalling system, the combination of a two part roadside element, means for imparting to one part an indication of the condition of the block next ahead and to the other part an indication of the condition of the immediate block, a train carried device passing over said parts in rapid succession, separate train carried signals, and means for 105
- 40 energizing one of said signals when said device is passing over one part and for energizing another of said signals when said device passes over said second part, said last named means comprising a three position selector, a primary relay and a secondary relay. 110

33. A railway cab signalling system comprising a track divided into insulated blocks, roadside signalling means at the entrance to each block and train carried means, operable 120
- 55 by said roadside means, comprising a selector operable first in accordance with the condition of the block next ahead, then in accordance with the condition of the immediate block at the entrance to each block, a primary 125
- 60 relay, a secondary relay, signals for indicating the condition of the block next ahead, signals for indicating the condition of the immediate block, and circuit means controlled by said selector and said relays for 130
- 65 first energizing a signal for the block next

ahead and next energizing a signal for the immediate block.

Signed at Niagara Falls in the county of Niagara and State of New York this 1st day of September A. D. 1926. 70
